UNITED STATES PATENT OFFICE

ALBERT JEFFERSON SAMS, OF CHICAGO, ILLINOIS

ROLLER CONTACT OILER

Application filed December 26, 1928. Serial No. 328,567.

This invention aims to provide a simple means for oiling the journals of locomotive wheels, car wheels, and anything else to which the invention may properly be applied.

More specifically, the invention aims to provide a simple means whereby the roller may be kept in contact with the journal, the roller extending far enough into the oil so as to carry oil to the journal.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:—

Figure 1 shows in end elevation, a device constructed in accordance with the invention, parts being broken away, and parts being in section;

Figure 2 is a section on the line 2—2 of Figure 1;

Figure 3 is a top plan of the oil reservoir or box;

Figure 4 is an end elevation of the structure shown in Figure 3;

Figure 5 is a section on the line 5—5 of Figure 3;

Figure 6 is a horizontal section taken through the oil reservoir and parts therein;

Figure 7 is a top plan showing the levers;

Figure 8 is a vertical section taken through that part of the oil reservoir which contains the float mechanism;

Figure 9 is a sectional view of one of the levers with the roller therein;

Figure 10 is a view like Figure 1, but showing a modification;

Figure 11 is a section on the line 11—11 of Figure 10;

Figure 12 is a sectional view of the box-like casing shown in Figure 11.

Figure 13 is a plan of the casing, the end closure having been removed, as in Figure 12; Figure 14 is a plan of the base plate which carries the springs;

Figure 15 is an elevation of the end closure 55 for the casing of Figure 13.

In Figures 1 to 9, the numeral 1 designates a journal frame, which may be taken as typical of a frame to be used on a locomotive engine, cars and elsewhere. Within the frame 60 1 is located a bearing 2 which receives the journal 3 of an axle 4, which may be the axle of an engine, a car, or any other vehicle. In carrying out the invention, there is provided an oil reservoir 5 preferably in the form of 65 a box. The ends of the reservoir 5 are shaped, as at 7, to cooperate with the journal 3. The oil box 5 is mounted in the frame 1 below the journal 3. The oil box 5 has depending ears 8 through which pass securing elements 70 9, such as bolts, which hold the oil box in the frame 1.

In one end of the oil box 5 there is an oil inlet hole 10. A partition 11 extends across one corner of the oil box 5, but does not extend down to the bottom of the oil box (Figure 8), the partition forming a chamber into which the oil can enter from within the oil box. A float 12 operates in the float chamber. A flexible element 14, such as a chain, is connected at one end to the float 12 and slides in an opening 15 in the end wall of the oil box. Upon the outer end of the chain 14 there is a weight 16 which takes the slack out of the chain. 85

The construction is such that a glance at the chain 14 and the weight 16 (Figure 1) will be sufficient to advise the operator how much oil there is in the oil box.

The end walls of the oil box 5 have bosses 90 24 which form places of mounting for the ends of fulcrum shafts 17 and 18 which extend across the oil box 5.

A lever, marked generally by the numeral 19, is provided, and is located within the oil box 5. The lever 19 is U-shaped in top plan, as Figure 3 will show: it includes a weight 95 20 and arms 21, the arms having spacing bosses 23 through which the shaft 18 passes, the lever 19, thus, being fulcrumed intermediate its 100

ends on the shaft 18. The spacing bosses 23 cooperate with the end walls of the oil box 5, as shown in Figure 6, and facilitate a free swinging movement of the lever 19 on its fulcrum 18. In the inner ends of the arms 21 of the lever 19 there are holes 22 in which is mounted a shaft 25. A roller 26 is carried for rotation by the shaft 25 and is located between the arms 21 of the lever 19. The numeral 27 designates a lever, which is like the lever 19, that is, U-shaped in top plan. The lever 27 includes an intermediate portion, or weight 28, and arms 29, the arms 29 being mounted on the shaft 17.

15 The lever 27, thus, is fulcrumed intermediate its ends. The levers 19 and 27 are provided respectively with bosses 23 and 30 which space the levers from the end walls of the box 5 and permit the levers to swing 20 freely in a vertical direction. The inner ends of the arms 29 are marked by the numeral 31, and, as shown in Figure 1, they engage beneath the inner ends of the arms 21 of the lever 19. The lever 27, therefore, cooperates 25 with the lever 19 to raise the roller 26 and to cause the roller to bear upon the journal 3 of the axle 4.

The device is simple in its operation, and 30 may be dismissed in a few words. The roller 26 dips into the oil in the box 5. When the journal 3 rotates, the roller 26 rotates also, because the roller is in contact with the journal, and when the roller rotates, oil is supplied to the journal.

35 It will be understood that the size of the roller may be varied to meet conditions, that is, the depth of the oil reservoir, the diameter of the journal, etc. The smaller the roller, the higher the speed at which it rotates, 40 and the journal may be adequately lubricated, according to speed, by providing a roller of proper diameter: that is, if the journal is turning rapidly, a roller of small diameter may be provided, so that the roller 45 will turn rapidly and afford an ample supply of oil.

The advantages of a device of the class described are marked. When grease cake lubrication is resorted to, as is done at present, 50 the lubrication is not thorough, and this is especially true in cold weather. The roller method shown in the present case will remedy the defects common to cake lubrication. In the case of a locomotive engine, the engine 55 will operate more freely and start more readily when equipped with the device shown in the drawings, this being true because lubrication is provided at all times. The same advantages obtain in large measure with 60 respect to car lubrication, and the opportunity for stealing oil, saturated waste, and the like, from the bearing box, is reduced to a minimum.

Referring to Figures 10-15, the numeral 65 122 marks a journal frame, within which is

located a bearing 123 which receives the journal 124 of the axle 125. A reservoir or oil box 126 is provided, and the ends of the reservoir are shaped at 127, as hereinbefore explained, to cooperate with the journal 124.

70

The oil box 126 is provided on its upper edge with a groove 128, and the upper edge of the oil box fits in a groove 129 formed in a resilient packing 130 having a depending tongue 131 received in the groove 128 of the oil box or reservoir 126. The packing 130 is pressed up against the lower edge of the bearing 123, and leakage of oil thereby is prevented. The oil applying device is designated as a whole by the numeral 132, and is dismissed with the remark that it is constructed like the structure shown at 26-19 etc. in Figure 1, and hereinbefore described.

80

The reservoir 126 is held in a box-like casing 133, for vertical sliding movement. The casing is provided at one end with threaded studs 134, received in slots 135 in an end closure plate 136, nuts 137 being threaded on the studs 134 to hold the closure 136 in place on the end of the casing 133. The casing 133 is held in the journal frame 122 by bolts 138 extended through holes 139 in the casing 133. A base plate 140 is located in the casing 133 and carries compression springs 141 which exert an upward thrust 95 on the reservoir 126 and maintain the packings 130 in contact with the bearing 123 between the journal 124 and the wall of the frame 122 to prevent leakage or slopping out of the oil, the oil being indicated at 142.

100

What is claimed is:—

1. In a device of the class described, an oil reservoir, a pair of levers fulcrumed in the reservoir, the inner end of one lever being engaged beneath the inner end of the other lever, an oil applying member on the inner end of the last specified lever, and the outer ends of the levers being so weighted as to press the oil applying member against the part to be lubricated.

105

2. In a device of the class described, an oil reservoir, a pair of levers fulcrumed in the reservoir, the inner end of one lever being engaged beneath the inner end of the other lever, an oil applying member on the end of the last specified lever and means cooperating with the outer ends of the levers for tilting them, to press the oil applying member against the part to be lubricated.

115

3. A device of the class described, constructed as set forth in claim 1, and further characterized by an abutment, a packing between the oil reservoir and the abutment, and means for yieldably pressing the reservoir against the packing.

120

In testimony that I claim the foregoing as my own, I have hereto affixed my signature.

ALBERT JEFFERSON SAMS.
